(57) **CLAIM**

The ornamental design for a shoe, as shown and described.

DESCRIPTION

FIG. 1 is a front perspective view of an embodiment of a shoe. FIG. 2 is a rear perspective view of the shoe of FIG. 1.

FIG. 3 is a right side view of the shoe of FIG. 1.

FIG. 4 is a left side view of the shoe of FIG. 1.

FIG. 5 is a rear view of the shoe of FIG. 1.

FIG. 6 is a bottom view of the shoe of FIG. 1; and,

FIG. 7 is an enlarged view of the encircled area of a lateral side of a midsole of the shoe seen in FIG. 4.

The vertical dash-dot broken lines located on the lateral side of the midsole of the shoe in FIG. 4 represent an unclaimed boundary of the claimed design. The dash-dot rectangle located inside the claimed area of the lateral side of the midsole in FIGS. 4 and 7 is included to indicate an enlarged view of the claimed area of the lateral side of the midsole only and forms no part of the claimed design.

The broken lines that appear over portions of the midsole and outsole regions represent unclaimed portions of a pattern thereon and form no part of the claimed design.

The stippled surface shading in the enlarged view of the claimed area of the lateral side of the midsole in FIG. 7 represents a three-dimensional appearance of the entire claimed area of the lateral side of the midsole in FIG. 4. The stippled surface shading of the entire claimed area of the lateral side of the midsole was omitted from FIG. 4 for clarity of illustration.

The remainder of the shoe shown in broken lines is for environmental purposes only and forms no part of the claimed design.
